US0D1055200S

(12) **United States Design Patent** (10) **Patent No.:** **US D1,055,200 S**
Mahnke (45) **Date of Patent:** **** Dec. 24, 2024**

(54) **PROJECTILE**(71) Applicant: **G9 Holdings, LLC**, Lakewood, CO (US)(72) Inventor: **Joshua Mahnke**, Post Falls, ID (US)(73) Assignee: **G9 HOLDINGS, LLC**, Lakewood, CO (US)(***) Term: **15 Years**(21) Appl. No.: **29/872,542**(22) Filed: **Mar. 14, 2023****Related U.S. Application Data**

(60) Division of application No. 29/714,930, filed on Nov. 26, 2019, now Pat. No. Des. 980,941, which is a division of application No. 29/612,522, filed on Aug. 1, 2017, now Pat. No. Des. 868,199, which is a continuation of application No. 15/406,781, filed on Jan. 16, 2017, now Pat. No. 10,502,536.

(57)

CLAIM

The ornamental design for a projectile as shown and described.

DESCRIPTIONFIG. 1 is a perspective view of the projectile;
FIG. 2 is a front elevation view thereof, which is the same as the rear elevation view, top plan view, and bottom plan view;FIG. 3 is a left elevation view thereof; and,
FIG. 4 is a right elevation view thereof.

The broken lines depict portions of the projectile in which the design is embodied that are not considered part of the claimed design.
